UNITED STATES PATENT OFFICE.

CHARLES H. ALLISON, OF GLENDALE, CALIFORNIA.

SUBAQUEOUS-BLASTING SYSTEM.

1,239,247.

Specification of Letters Patent. Patented Sept. 4, 1917.

Application filed April 21, 1917. Serial No. 163,600.

To all whom it may concern:

Be it known that I, CHARLES H. ALLISON, a citizen of the United States, residing at Glendale, in the county of Los Angeles, 5 State of California, have invented new and useful Improvements in Subaqueous-Blasting Systems, of which the following is a specification.

This invention relates to systems and devices particularly adapted for explosive work under water; and the invention has for its general object the provision of an efficient system of sub-aqueous blasting of any kind; and, particularly for blasting and 10 other explosive work in great depths of water. I have developed my system and the component parts of its apparatus with especial reference to blasting wells, where such work must frequently be carried on 15 in very excessive depth of water, sometimes exceeding a mile; but it will be understood, from the nature of the devices themselves, and from the following specification, that my invention, and this system, are not limited 20 to such specific use, and are not, in some cases, even limited to aqueous blasting.

In order to make my invention most clearly apparent in all its scope and detail, I may briefly describe the method and system 25 most universally in previous use. For most kinds of work of the character herein indicated, it has become very usual and prevalent to use a relatively insensitive explosive. For instance, gelatin has come into 30 very prevalent use, both on account of its great explosive strength and force, and on account of its relative safety due to its insensitivity.

But this insensitivity, coupled also with 35 a lack of self-detonation, has made it necessary to use a very strong detonator to obtain the utmost efficiency from the gelatin; and has further necessitated the use of detonators at frequent intervals throughout 40 the length of a charge of gelatin in order to efficiently detonate the whole charge of gelatin. Such explosives as these are not good conductors of the explosive wave. In 45 actual practice it has therefore become necessary to place detonating caps, or bundles of detonating caps, at frequent intervals throughout a large or long charge of gelatin or similar explosive; in practice these caps, or bundles of caps, being placed from twenty 50 to thirty inches apart.

When such insensitive explosives are

placed under great water pressure their insensitivity and non-conductiveness of the explosive wave increases as the pressure increases; and consequently, at great depth 60 under water, it is quite necessary to use very strong detonators at frequent intervals throughout the entire length of the charge in order to develop the maxim of efficiency of the explosive charge. 65

I have substituted for the explosive caps, or the bundles of caps, placed at intervals throughout the length of the explosive charge, a continuous detonating fuse, of the type known as "Cordeau"; being a fuse-like body comprising a tube containing a very strong explosive in which the detonation travels with extreme rapidity and causes a very great explosive or detonating effect. I extend such a detonating fuse 70 throughout the length of a gelatin or other explosive charge; and then, by detonating the fuse, I cause almost instantaneous detonation of the whole explosive charge; and I cause thorough detonation of 75 the explosive charge at its highest efficiency.

The means and arrangements by which I cause detonation of the detonating fuse is one of the elements of this system and of this invention. I have found that such a 80 detonating fuse as "Cordeau" will retain its efficiency under great pressure provided the water is not allowed access to the interior of the tube to the explosive. The tubular container of such a fuse is usually of lead 85 or other soft metal; and this tubular container is therefore relatively compressible by exterior pressure; but great exterior pressure can be borne by the explosive itself and does not detract from its detonating 90 powers. Consequently, I take a length of such a detonating fuse and close one end, by sealing the tube; and then make arrangements of an explosive cap or caps in such 95 relative position to the end of the fuse as 100 to cause initial detonation of the fuse at that end; and I provide means for waterproofing and for protecting the end of the fuse and the cap against great pressure. Such means are shown in my issued Letters 105 Patents Nos. 1,094,692, April 28, 1914; 1,163,965, December 14, 1915; and 1,215,329, February 13, 1917; and the waterproofing and pressure protective means herein described are developments, improvements and 110 adaptations of said devices. Furthermore, I provide means for concentrating the ex-

plosion, or the explosive wave created by the cap, onto the end of the detonating fuse; and I may also provide a second explosive cap to augment the explosive and detonating effect of the cap.

All of these foregoing indicated features, together with the various details of structure and arrangement, and further objects and features of this invention are explained 10 in the following specification. In this specification I describe in detail a preferred arrangement and combination of devices embodying my invention and accomplishing the objects herein set forth; and for the 15 purposes of this specification I refer to the accompanying drawings in which Figure 1 is a longitudinal central section showing a preferred construction and arrangement of a complete blasting system or organization, 20 according to my invention; Fig. 2 is an enlarged central longitudinal section illustrating the connection of the explosive cap to the detonating fuse; Fig. 3 is a similar section showing the caps in elevation; Fig. 4 is a vertical section of a well casing showing my devices in elevation therein. Fig. 5 is a cross section taken as indicated by line 25 5—5 on Fig. 1, and Fig. 6 is a cross section taken as indicated by line 6—6 on Fig. 2.

30 Referring now more particularly to the drawing: I illustrate at 10 (Fig. 4) a well casing and show the general relation of an explosive charge thereto. In actual practice, in deep well work, the explosive charge is 35 put into long tubular cans 11; and a single tubular can may hold the complete charge, or a number of such cans may be connected together end to end, for the purpose of carrying a heavy charge, also for the purpose of 40 distributing a charge over a great length of the well or casing. I show such cans as are generally used in Figs. 1 and 4. These cans are preferably made of sheet iron pipe and are provided with a conical bottom cap 12 45 and with a suitable suspension bail 13, at their upper ends. Two or more such cans may be connected together in the manner best shown in detail in Fig. 1. A plurality of wire loops 14 may be used to connect 50 adjacent cans together; and short lengths of pipe or tubing, shown at 15, may be used to space the cans apart, so as to preclude or minimize any tendency of the cans to move 55 relatively to each other. This arrangement 60 is of particular importance in view of the fact that the detonating fuse, which I extend in a single length throughout all of the interconnected cans, is liable to be broken if it is sharply bent, twisted, or turned at 65 any point. In order to further minimize any difficulties of this sort, I provide the detonating fuse 16 with an expansion and contraction coil 16^a at the point where it extends between adjacent connected cans.

65 The bottom 12 of one can may have a suit-

able opening 12^a therethrough to allow the detonating fuse passage.

Each can is filled with the explosive charge in any suitable manner, and the detonating fuse 16 is placed centrally lengthwise of the charge. For instance, in using gelatin, I fill the cans with cylindrical blocks or sticks of gelatin 20 cut to proper size to fit the can; and each block or stick of gelatin is slit, as shown in Fig. 5; so that 70 the detonating fuse 16 may extend lengthwise through the blocks. The uppermost block of gelatin may have a larger sized opening 21^a at its center to accommodate the protected cap and fuse connection device 22. 75 This device 22 is preferably set down within the top of the uppermost can and within the gelatin, so that it is held in a relatively immovable position; and the two line wires 23, which lead out from the cap arrangement, are lashed or otherwise suitably secured, as indicated at 24, to the cable, wire, 80 or rope, or other suspension means 25, by means of which the explosive charge is lowered into the well. The line wires 23 extend up along the cable to the top of the 85 well.

The extreme lower end of the detonating fuse 16 is closed. This is accomplished preferably by sealing the end of the leaden tube 30, after a suitable amount of the explosive substance 31 has been melted out. The sealed end is shown at 32 in Fig. 2. In my preferred device I provide, at the upper end of the detonating fuse, a suitable shell 33 having a longitudinal bore 34; the part 34^a of the bore being adapted to receive the upper end of the detonating fuse and to receive an ordinary explosive cap 35; and the upper part 34 of the bore adapted to receive 105 an electric cap 36. This electric cap 36 fits down into the bore against the cap 35, with its upper end fitting in an enlarged or recessed portion 34^b of the bore, and the upper end of the cap being preferably somewhat 110 below the extreme upper end of the bore. The exterior diameter of the detonating fuse (of the leaden tube 30) and the exterior diameter of the shell 35^a of the cap 35 are very nearly the same; and the upper end 115 part 30^a of the leaden tube 30 is scraped down, or otherwise reduced in diameter, so that it will fit into the open end of the cap shell 35^a, with the exposed end of the detonating material 31 directly against a small 120 wadding of cotton 37 which is put into the cap to protect the explosive substance 38 thereof against frictional contact with the end of the detonating fuse. This wadding of cotton only separates the explosive material 38 (usually fulminate of mercury) and the end of the detonating fuse 16 by a short distance; so that the open end of the detonating fuse is practically against the explosive material of the cap 35. When the det- 125 130

onating fuse is inserted in the cap shell 35^a it is first dipped in melted asphalt, tar or some similar substance, which substance then seals the end of the detonating fuse into the 5 open end of the shell; and when the shell and the detonating fuse are then inserted together in the bore 34^a of the exterior shell 33, they are both dipped in the melted plastic sealing substance and then inserted. 10 The result is that both the cap 35 and the end of the detonating fuse are sealed into the exterior shell 33 by a thin film or coating of the plastic substance, as shown at 40; and the upper end of the detonating fuse is 15 sealed into the open end of the cap shell by a similar thin film or coating of the same substance as shown at 41. The film or coating 40 extends out to the outer end of the exterior shell 33 and afterward unites with the 20 final exterior coating of the same substance which is applied to the exterior of the shell 33. The same procedure is adopted with the electric cap 36; this cap being dipped in the same substance and then inserted in the 25 bore 34; being thus sealed in the bore, and completely surrounded, by a thin film or coating of substance, as shown at 42. Any excess of the plastic substance on the cap 36 will be squeezed up and out into the 30 larged portion 34^b of the bore around the upper end of the cap and will subsequently be united with the final outer covering of the same substance which is applied to the shell 33, as hereinafter described. The line 35 wires 23 are joined to the cap wires 43, as shown at 44, as closely as practicable to the cap; so that these joints in the wires lie well inside the final plastic covering which is given to the whole device 22. Each of the 40 shells of caps 35 and 36 is preferably provided with an aperture 45 to allow access of the exterior pressure to the interior of the cap shells, through the medium of the plastic substance forming the coatings 40 and 45. Although I have found that the protection given to the caps by the general method herein employed is usually sufficient without providing the openings at 45; yet I have found that by providing the openings 45 and allowing the exterior pressure to be 50 transmitted to the interiors of the caps, I am enabled to lower the caps to the greatest of distances beneath the water surfaces without the caps being deformed by the external pressure and without their being prematurely exploded by reason of such deformation or being so deteriorated by such deformation that they cannot be properly exploded when so desired. The uniform 55 pressure upon the material within the cap does not deteriorate it or prematurely explode it, or prevent its being exploded when so desired; but deformation of the cap shell by reason of exterior pressure, without a 60 balancing interior pressure, causes such a

deformation of the cap shell as to sometimes prematurely explode them or to render their explosion impossible when the shells are lowered to exceptionally extreme depths of water. 70
The exterior shell 33 is preferably made of metal with sufficiently strong walls to withstand the exterior pressure and to withstand the internal explosion of the caps and of the part of the detonating fuse contained 75 therein. It will be understood, however, that with the provisions herein described, it is not necessary to provide the shell 33 with strong walls in order to protect the caps and the upper end of the detonating fuse from 80 the external water pressure; with the means herein described, it is only necessary to seal these parts from direct access of water and to provide for an equalization of pressures as herein stated. In this connection I refer 85 particularly to my Letters Patents herein-before enumerated and referred to; wherein the general principles of cap protection against moisture and against water pressure are fully set forth, applied to various circumstances, and the devices for such applications claimed. It will be noted that the present described device includes and embodies certain principal features of the devices described and claimed in said Letters 90 Patents; but embodies further the certain combinations, organizations and improvements herein set forth for adapting the arrangements to the particular purposes and to the major combination herein described. 95 One of the particular features of the shell 33 is that I preferably make it with sufficiently strong walls to withstand internal explosion and to consequently direct and concentrate the explosion of the caps, or the 100 explosive wave created by the caps, longitudinally onto the end of the detonating fuse. It will be seen that my arrangement comprises generally a means for positioning a cap and the end of the fuse in juxtaposition and for causing efficient initiation of 105 detonation in the fuse from the explosion of the cap. The electric cap 36 may be looked upon as the primary cause of the detonation of the fuse; or the ordinary cap 35 may be looked upon as the cause (the immediate cause) of the detonation of the fuse. I prefer to describe the cap 35 as a "booster", in that it augments the explosive action of 110 the cap 36 and causes a sure and efficient 115 initiation of detonation in the fuse. The position of the "booster" cap 35 allows me to put the open exposed end of the detonating substance 31 of the fuse practically into direct contact with the exposed end of the explosive substance 38 of the cap 35; and this specific arrangement adds to the efficiency of 120 action.
After the fuse and the caps have been inserted in the shell 33, then an exterior coat- 125
130

- ing 50 of the same plastic substance is applied, preferably while warm enough to be kneaded, to the outside of the shell, the substance being forced into the open upper end 5 of the shell 33 and being kneaded into intimate juncture with the coatings 40 and 42; being at the same time kneaded closely around the detonating fuse 16 and around the line wires 23, and the wire joints 44 being 10 covered and inclosed within this coating or covering. The end parts of this covering (the parts at the ends of the shell 33) may be kneaded into place, and the complete covering around the whole length of the shell 15 may be also put into place in the same manner; or the relatively thin part 50^a which surrounds the cylindrical surface of the shell may be formed by merely finally dipping the whole arrangement in liquid asphalt. 20 In any case, the whole arrangement is usually finally dipped in liquid asphalt so as to form an exterior soft surface upon which a taping, preferably of rubber, as shown at 51, may be immediately wound and held by 25 the adhesiveness of the plastic substance. This taping is put on for the mechanical protection of the plastic substance from abrasion, etc.

When I say plastic substance, I do not 30 necessarily mean a substance which is plastic at ordinary temperatures or pressures, although it may be so. For instance, the substance which I use for coating and sealing in the caps and the fuse and for coating 35 the whole device 22 is an asphalt or tar or the like, and this substance may be quite hard and brittle at ordinary temperatures or pressures; but it moves under high pressure. I do not conceive of my invention as being 40 limited to the particular and specific devices, etc., herein set forth, but as being of a broad nature and covering those general combinations of which the described devices are indicative. I have consequently proceeded to 45 describe a preferred form of system embodying my invention, not for the purposes of limitation, but for the purposes of indicating and typifying what forms my invention may take. And the following claims are 50 therefore drawn to briefly cover the different main and subsidiary combinations, parts and elements, herein set forth, both broadly and specifically.

Having described a preferred form of my 55 invention, I claim:

1. In a device of the character described, in combination with a detonating fuse, a shell having a longitudinal bore adapted to receive one end of the fuse, the fuse being 60 otherwise exterior of the shell, an explosive cap in the shell bore to initiate the detonation of the fuse, and a protective covering around the shell, the cap and said fuse end to protect them against water pressure.
- 65 2. In a device of the character described,

in combination with a detonating fuse, a shell having a longitudinal bore adapted to receive one end of the fuse, the fuse being otherwise exterior of the shell, an explosive cap in the shell bore to initiate the detonation of the fuse, and a protective covering of plastic water-proof material surrounding the shell, the cap and the fuse end. 70

3. In a device of the character described, in combination with a detonating fuse, a shell having a longitudinal bore extending from end to end and adapted at one end to receive one end of the fuse, an electric explosive cap in the bore with its firing wires extending out of the other end of the bore, and a protective covering of plastic water-proof material surrounding the shell and said fuse end and extending over the end of the cap and around its firing wires. 75

4. In a device of the character described, in combination with a detonating fuse, a shell having a longitudinal bore extending from end to end and adapted at one end to receive one end of the fuse, the walls of the shell being of explosive resisting strength 90 and the shell thus adapted to concentrate the explosive wave of the cap longitudinally onto the end of the detonating fuse, an electric explosive cap in the bore with its firing wires extending out of the other end of the bore, and a protective covering of plastic water-proof material surrounding the shell and said fuse end and extending over the end of the cap and around its firing wires. 95

5. In a device of the character described, in combination with a detonating fuse, a shell having a longitudinal bore adapted at one end to receive one end of the detonating fuse, an explosive cap in the bore, and a protective covering of plastic waterproof material around the ends of the shell and extending into the shell bore around the fuse end and around the cap. 100

6. In a device of the character described, in combination with a detonating fuse, a shell having a longitudinal bore adapted at one end to receive one end of the detonating fuse, an explosive cap in the bore, and a protective covering of plastic waterproof material around the ends of the shell and extending into the shell bore around the fuse end and around the cap, the cap being composed of a cap shell and contained explosive material, and the cap shell having a perforation to allow access of exterior pressure to the interior of the cap shell through the medium of the plastic material. 110

7. In a device of the character described, in combination with a detonating fuse, a shell having a longitudinal bore receiving 125 bore, an explosive cap in the bore in longitudinal juxtaposition to the fuse end, and an electric cap in the bore in juxtaposition to the first mentioned cap.

8. In a device of the character described, 130

in combination with a detonating fuse, a shell having a longitudinal fuse receiving bore, an explosive cap in the bore embodying a cap shell containing explosive material, 5 the end of the detonating fuse entering the open end of the cap shell and being in longitudinal juxtaposition to the explosive material therein, and an electric cap in the bore in longitudinal juxtaposition to the first 10 mentioned cap.

9. In a device of the character described, in combination with a detonating fuse, a shell having a longitudinal fuse receiving bore, an explosive cap in the bore embodying 15 a cap shell containing explosive material, the end of the detonating fuse entering the open end of the cap shell and being in longitudinal juxtaposition to the explosive material therein, an electric cap in the bore in 20 longitudinal juxtaposition to the first mentioned cap, and a protective covering of waterproof plastic material over the ends of the first mentioned shell and extending into its bore around the end of the fuse and 25 around the explosive caps, each of the cap shells being perforated to allow access of exterior pressure to the interiors of the caps through the medium of the plastic material.

10. In a device of the character described, 30 in combination with a detonating fuse, a shell having a longitudinal bore extending from end to end and adapted at one end to receive one end of the fuse, the walls of the shell being of explosion resisting 35 strength, an open ended explosive cap in the bore near the end receiving the fuse, the end of the fuse being entered into the open end of the cap and being in juxtaposition to the explosive material thereof, an electric 40 cap in the other end of the shell bore in longitudinal juxtaposition to the first mentioned cap, the outer end of the electric cap being somewhat inside the end of the bore, line wires connected to the electric cap firing 45 wires close to the end of the bore, and a protective covering of plastic waterproof material around the ends of the shell and around the wire connections and extending into the bore at both ends and extending 50 around the caps and the end of the fuse. 55

11. In a device of the character described, in combination with a detonating fuse, a shell having a longitudinal bore extending from end to end and adapted at one end to receive one end of the fuse, the walls of the shell being of explosion resisting strength, an open ended explosive cap in the bore near the end receiving the fuse, the end of the fuse being entered into the open end of 60 the cap and being in juxtaposition to the explosive material thereof, an electric cap in the other end of the shell bore in longitudinal juxtaposition to the first mentioned cap, the outer end of the electric cap being 65 somewhat inside the end of the bore, line

wires connected to the electric cap firing wires close to the end of the bore, and a protective covering of plastic waterproof material around the ends of the shell and around the wire connections and extending 70 into the bore at both ends and extending around the caps and the end of the fuse, each of the caps comprising a cap shell containing the explosive material, the cap shells being perforated to allow access of exterior 75 pressure to the cap interior through the medium of the plastic material.

12. In a device of the character described, in combination with a detonating fuse, a shell having a longitudinal bore extending 80 from end to end and adapted at one end to receive one end of the fuse, the walls of the shell being of explosion resisting strength, an open ended explosive cap in the bore near the end receiving the fuse, the end of the fuse being entered into the open end of the cap and being in juxtaposition to the explosive material thereof, an electric cap in the other end of the shell bore in longitudinal juxtaposition to the first mentioned 85 cap, the outer end of the electric cap being somewhat inside the end of the bore, line wires connected to the electric cap firing wires close to the end of the bore, and a protective covering of plastic waterproof material around the ends of the shell and around the wire connections and extending into the bore at both ends and extending 90 around the caps and the end of the fuse, each of the caps comprising a cap shell containing the explosive material, the cap shells being perforated to allow access of exterior pressure to the cap interior through the medium of the plastic material; the plastic material superficially completely covering 95 the first mentioned shell; and a mechanically protective taping around the plastic coating.

13. In a device of the character described, the combination of a detonating fuse embodying a waterproof tubular container and a detonating material therein, the tubular container being closed at one end to prevent entry of water, an explosive cap at the end of the detonating fuse, and a waterproofing 110 covering surrounding the cap and the adjacent end of the fuse.

14. In a device of the character described, the combination of a detonating fuse embodying a waterproof tubular container and a detonating material therein, the tubular container being closed at one end to prevent entry of water, an explosive cap at the other end of the detonating fuse, and a waterproofing covering of plastic material surrounding the cap and the adjacent end of the fuse.

15. In a device of the character described, the combination of a detonating fuse embodying a waterproof tubular container and 130

a detonating material therein, the tubular container being closed at one end to prevent entry of water, an explosive cap at the other end of the detonating fuse, a longitudinally 5 bored shell receiving the cap and the adjacent end of the fuse to hold the cap and fuse in longitudinal juxtaposition and to concentrate the explosion of the cap onto the end of the fuse, and a covering of plastic 10 waterproof material around the shell, the cap and the fuse end.

16. In a device of the character described, the combination of a detonating fuse embodying a waterproof tubular container and 15 a detonating material therein, said container being compressible by exterior pressure and closed at one end to prevent entry of water, a shell of relatively non-compressible material with explosion resisting walls receiving 20 the other end of the detonating fuse, a cap in the shell adjacent said end of the fuse, and a covering of plastic waterproof material surrounding the ends of the shell and the cap and said end of the fuse.

25 17. In a device of the character described, the combination of a fuse embodying a waterproof tubular container closed at one end to prevent entry of water, an explosive cap at the other end of the fuse, and a 30 water proofing covering surrounding the cap and the adjacent end of the fuse.

18. In a device of the character described, the combination of a fuse embodying a 35 waterproof tubular container closed at one end to prevent entry of water, an explosive

cap at the other end of the fuse, and a pressure protective covering surrounding the cap and the adjacent end of the fuse.

19. An explosive device for deep water work embodying in combination a body of explosive unaffected by water pressure and unprotected therefrom, a detonating fuse extending through the body of explosive, an explosive cap arranged at one end of the fuse, and means surrounding the cap and 45 that end of the fuse to protect it from water pressure.

20. An explosive device for deep water work, embodying in combination a body of explosive unaffected by water pressure and 50 unprotected therefrom, a detonating fuse extending through the body of explosive, and closed against water pressure at one end, an explosive cap arranged at the other end of the fuse, and means surrounding the cap 55 and that end of the fuse to protect them against water pressure.

21. An explosive device for deep water work, embodying in combination a body of explosive unaffected by water pressure, a 60 detonating fuse extending through the body of explosive and closed against water pressure at one end, an explosive cap at the other end of the fuse, and means surrounding the cap and that end of the fuse to protect them 65 against water pressure.

In witness that I claim the foregoing I have hereunto subscribed my name this 13th day of April, 1917.

CHARLES H. ALLISON.
